Their Attorney.

UNITED STATES PATENT OFFICE

2,097,556

AIR CONDITIONING APPARATUS

Ralph F. Bixby and John H. Meyer, St. Louis,
Mo.; said Meyer assignor to said Bixby

Application November 5, 1934, Serial No. 751,610

7 Claims. (Cl. 62—91.5)

Our invention relates to air conditioning apparatus and more particularly to such apparatus as is adapted to cool and otherwise condition the air in a small space such as a room or a group of several rooms as contra-distinguished from apparatus designed to condition the air in large buildings. Likewise, our invention, while it may be used in apparatus of various kinds, is more particularly adapted for use in a unitary structure wherein all of the various parts are included in a cabinet.

Heretofore, air conditioning apparatus of the usual type included a compressor for one of the usual type of refrigerating fluids and an evaporator or coil in which the fluid expanded to cool the air passing through and around the coil. Of course, such apparatus was extremely costly to manufacture and depreciation and cost of upkeep was high.

Likewise, if the necessary apparatus for a machine of the type described was included in a single cabinet the weight of the compressor and other parts was such that the cabinet could be moved only with great difficulty from one part of a room to another part or from room to room.

Furthermore, in the use of air conditioning apparatus in the past operation was controlled by a thermostat fixed in one position in the space being cooled and oftentimes all the air was not properly conditioned because the thermostat control was so fixed, and with the outside weather varying the temperatures at different parts of the room would not be the same.

Attempts have been made to provide air conditioning apparatus using charges of solidified carbondioxide (CO₂) or similar low temperature refrigerants, but because of the obstacles presenting themselves to the use of such refrigerants these devices have been inefficient and, in many cases, inoperative.

The objects of our invention are to provide an air conditioning apparatus which may be contained and embodied in a light cabinet in a manner which permits cheap manufacture, to provide such apparatus whereby the control thereof may be governed by conditions and temperatures at any one of an infinite number of desired points in the space being cooled and to provide an air conditioning apparatus which may utilize CO₂ as the refrigerant in a manner never before taught.

Although, of course, our invention may be used in many different types of embodiments, in the accompanying drawing we have shown our invention as embodied in one form of device. In

the drawing Fig. 1 is a view, partly in section, of the apparatus in elevation and Fig. 2 is a detail of structure.

Referring to the figures in the form shown therein all working parts of the device are included in a cabinet 1 which may be of any suitable size, shape, or design. Preferably, to facilitate movement of the cabinet from one place to another it is mounted on swivel rollers or casters 2. The cabinet includes an air conditioning compartment 3 and a receptacle 4 in which a heat exchange agent, such as brine or alcohol, is cooled by a charge of refrigerant inserted in a container 5. These divisions of the cabinet may be arranged in any relative manner. That is to say, they may be one above the other, a convenient arrangement, as shown in the figures or they may be side by side, if desired.

The receptacle 4 is, of course, closed and, preferably, is insulated by a surrounding body of cork, mineral wool or other similar material as indicated at 6. The container 5 is positioned in this embodiment within the receptacle 4 so that the walls thereof are spaced from the walls of the receptacle 4 whereby the heat exchange agent may freely circulate thereabout and be cooled by conduction through the walls of the container which are preferably of thin sheet metal or other conductive material. The container 5 is provided at one end with an opening 7 through which a charge of CO₂ or other low temperature refrigerant as indicated at 8, is placed. The opening 7 is normally closed by a closure 9 and, to prevent dissipation of heat through the opening a mat 10 of asbestos or other suitable insulating material is fitted into the open end of the container before the closure is moved into place.

The air conditioning compartment 3, preferably, is divided by a partition 11 into a space to receive a cooling coil 12 and a space to contain the operating parts of the apparatus. Such operating parts in this embodiment include a pair of blowers 13 mounted so as to expel air into the upper space of the compartment and past 45 and in contact with the coil 12.

A pump 19 passes the heat exchange agent through the coil, and a motor 16 drives both the blowers and the pump. While in this embodiment we have shown blowers for circulating the air we do not intend to limit ourselves to mechanical means of this particular type for this purpose because it is obvious that any of the various types of fans, blowers or other similar devices may be employed with equal facility. Likewise,

while the coil 12 is of the usual convoluted and finned type, operation of our device does not depend on such form of coil. In the specification and claims the term "coil" is used to denote 5 any form of structure through which a cooling agent may flow so as to cool air passing thereby.

The air after it is cooled by contact with the coil is forced from the cabinet through a grilles opening as at 14. The circuit of such air through 10 the room or other space in which the air is being conditioned is completed by drawing air to the blowers through the louvres 15 preferably positioned in a side wall of the cabinet below the partition 11.

15 As stated above the coil 12 may be of any suitable form, but in this embodiment it consists of a plurality of convolutions of a pipe 17 and a plurality of thin metal fins 18 having an intimate contact with said convolutions so as to be cooled 20 thereby. The pipe 17 has one end thereof leading from the receptacle 4, preferably at the lower side thereof, and has the other or return end thereof leading back to the receptacle, preferably at the bottom thereof. Under certain conditions 25 the flow of the heat exchange agent through the pipe may be caused by a thermo-syphon action naturally induced, but for best results we prefer that the circulation of the agent be mechanically induced by a pump 19 driven by the same motor 30 16 which operates the mechanical means for causing the circulation of air.

In some embodiments it is necessary to regulate the amount of agent being circulated through the coil and, therefore, we prefer that an adjustable valve similar to the needle type valve 20 35 shown in Fig. 2 be incorporated in the line below the pump.

In this embodiment operation of the blowers 13 and pump 19 may be manually controlled by 40 movement of an electric switch 21 or may be controlled automatically as determined by the temperature within the space being cooled by a portable thermostat 22, of the usual type, which is attached to the end of a long flexible cord 23 so 45 that it may be moved to any desired point. The thermostat, of course, is arranged so that when the temperature in the space being cooled at the given point rises, operation of the air conditioning apparatus is commenced and when the temperature has been lowered by such operation to 50 the desired degree, operation is stopped.

If CO₂ is used as the low temperature refrigerant the gases resulting from its evaporation are extremely cold and, therefore, these gases may be 55 allowed to flow from the container 5 through the pipe 24 which is convoluted with the resultant convolutions arranged in conductive association with the fins 18 of the coil 12 so that these fins are cooled further. The gases then may be 60 allowed to flow through an outlet 25 from the pipe 24 directly into the space being cooled or, if desired, may be conducted by a suitable hose or other conduit to an outside place of discharge. As air is blown over the coil 12 moisture will be 65 condensed on the parts of the coil and as this moisture drips therefrom onto the partition 11 it may drain to one side of the partition where it flows downwardly through the drain pipe 26 into the receptacle 27. At predetermined intervals 70 the resultant water may drain from the receptacle through a suitable valve-controlled faucet 28.

An understanding of operation of our device will be clear from the above description and it is 75 not believed that a detailed statement of such

operation is required. However, it will be apparent that our device will operate efficiently to cool and condition the air in a given space or room. Similarly, because of its light and simple construction our device may be moved quickly and 5 easily from one point or room to another.

As set forth above we have shown herein one embodiment only of our invention, but in other embodiments the size, shape and arrangement of the parts may be varied within wide limits without deviating from the spirit of the invention as included in the appended claims.

What we claim as new and desire to secure by Letters Patent is:—

1. An air conditioning apparatus comprising a 15 receptacle for a heat exchange agent, a container for a low temperature refrigerant positioned in intimate thermal contact with said agent, a casing forming an air treating compartment through which air may be circulated, a coil positioned in 20 said compartment in the path of circulation of said air, means for circulating said agent through said coil and a secondary coil positioned similarly to said first coil and means for passing through said secondary coil the gases resulting 25 from evaporation of said refrigerant.

2. An air conditioning apparatus comprising an insulated receptacle for a heat exchange agent, a container for a low temperature refrigerant positioned within said receptacle whereby said refrigerant will have an intimate thermal contact with said agent, a casing forming an air treating compartment through which air may circulate, a coil positioned in said compartment in the path of circulation of said air, means for 30 35 circulating said agent through said coil, and a secondary coil positioned similarly to said first coil and means for passing through said secondary coil the gases resulting from evaporation of said refrigerant.

3. An air conditioning apparatus comprising an insulated receptacle for a heat exchange agent, a container of conductive material adapted to receive a charge of low temperature refrigerant and positioned within said receptacle whereby 45 said refrigerant will be in intimate thermal contact with said agent, an opening through which said container may be charged, a closure for said opening, a casing forming an air treating compartment for treating air and having an inlet 50 therein to and an outlet therefrom, a coil positioned in said compartment in the path of circulation of said air, means for circulating said agent through said coil, and a secondary coil positioned similar to said first coil and means for 55 passing through said secondary coil the gases resulting from evaporation of said refrigerant.

4. An air conditioning apparatus comprising a suitable cabinet having a receptacle therein for a heat exchange agent, a container for a low 60 temperature refrigerant positioned in intimate thermal contact with said agent, said cabinet also having an air treating compartment for treating air with an inlet thereinto and an outlet therefrom, a coil positioned in said compartment 65 in the path of circulation of said air, means for circulating said agent through said coil, and a secondary coil positioned similarly to said first coil and means for passing through said secondary coil the gases resulting from evaporation of said 70 refrigerant.

5. An air conditioning apparatus comprising a suitable cabinet having an insulated receptacle therein for a heat exchange agent, a container for a low temperature refrigerant positioned with- 75

in said receptacle so as to be in intimate thermal contact with said agent, said cabinet also having an air treating compartment with an inlet thereto and an outlet therefrom, a coil positioned in 5 said compartment in the path of circulation of said air, means for circulating said agent through said coil, and a secondary coil positioned similarly to said first coil and means for passing through said secondary coil the gases resulting from evaporation of said refrigerant.

6. An air conditioning apparatus comprising a suitable cabinet having an insulated receptacle therein for a heat exchange agent, a container for a low temperature refrigerant positioned in intimate thermal contact with said agent, an opening through which said container may be charged, a closure for said opening, said cabinet also having an air treating compartment with an inlet thereto and an outlet therefrom, a coil positioned in 15 said compartment in the path of circulation of said air, means for circulating said agent through said coil, and a secondary coil positioned similarly to said first coil and means for passing through said secondary coil the gases resulting from evaporation of said refrigerant.

7. An air conditioning apparatus comprising a suitable cabinet having an insulated receptacle 5 therein for a heat exchange agent, a container for a low temperature refrigerant positioned in intimate thermal contact with said agent, an opening through which said container may be charged, a closure for said opening, said cabinet 10 also having an air treating compartment with an inlet thereto and an outlet therefrom, mechanical means for inducing a circulation of air through said compartment, a coil positioned in said compartment in the path of circulation of 15 said air, means for circulating said agent through said coil, and a secondary coil positioned similarly to said first coil and means for passing through said secondary coil the gases resulting from evaporation of said refrigerant.
